UNITED STATES PATENT OFFICE.

WILLIAM F. GEUPE, OF LYNDHURST, NEW JERSEY, ASSIGNOR TO HARRY H. STRAUS,
OF NEW YORK, N. Y.

CORK FACING.

Application filed July 18, 1923. Serial No. 652,265.

This invention relates to facings of cork for mangle rolls and the like.

An object of this invention is to provide for mangle rolls and the like a facing of improved construction for use with the usual wrapping of sheeting of duck, linen, cotton and the like, for attaining the required resistance for effecting the ironing of apparel and permitting buttons and like addenda of apparel to pass therethrough without breakage or other injury.

A further object of the invention is to provide a facing of the above character in a form capable of being readily applied to the mangle rolls and of being readily renewed as desired and at minimum expense.

With the above and other objects in view, a preferred form of my facing for mangle rolls and the like is formed of natural corkwood arranged as strips and constructed to be applied to the surface of the roll spirally relatively to the axis of the roll. An effective method of securing such strips of corkwood to the mangle roll is by means of grooves machined on the cylindrical face of the roll and having a predetermined width, inserting blocks of corkwood having a bottom extension of a width slightly greater than the width of the groove whereby upon compressing such extension within the groove, the strips formed of blocks of natural corkwood are retained therein.

In such preferred form, the blocks of corkwood for any one groove are secured to one another in longitudinal alignment to form a strip and the upper face of the cork is cut or grooved to enhance the bending or twisting of the corkwood and thereby facilitate the insertion of the corkwood within the groove and also improve the extent of yieldability of the corkwood during the ironing operations.

Further features and objects of the invention will be more fully understood from the following detail description and the accompanying drawings, in which—

Fig. 1 is a perspective view showing a strip formed of blocks of natural corkwood, secured longitudinally to one another and arranged for installation on the surface of the mangle roll;

Fig. 2 is a detail perspective view of a mangle roll having a series of helical grooves machined on the cylindrical face thereof and

strips of blocks of corkwood inserted therein, and the usual outer covering of canvas or sheeting or the like;

Fig. 3 is a detail transverse sectional view of a mangle roll shown in Fig. 2, on an enlarged scale, illustrating three grooves and the three strips of corkwood inserted therein;

Fig. 4 is a detail perspective view of a modified strip formed of blocks of natural corkwood secured longitudinally to one another;

Fig. 5 is a detail transverse sectional elevation similar to Fig. 3, showing the form of corkwood strip shown in Fig. 4; and

Fig. 6 is a detail perspective view showing a modification of strip of natural corkwood anchored to a carrier of metal or the like adapted to be inserted in the groove of the mangle roll.

Referring to Figs. 1, 2 and 3, the mangle roll 10 is of the usual construction, cylindrical in form and having the oppositely extending shafts 11 for insertion in the usual bearings. Usually three or more mangle rolls are mounted in substantial horizontal alignment with one another and coact with a curved bed of a hollow formed cast iron casting, which is supplied with steam for obtaining the necessary ironing temperature. Accordingly, in the ironing operation the apparel and other articles to be laundered pass successively between the mangle rolls and the heated bed upon rotation of the mangle rolls in the proper propelling direction.

Pursuant to my invention, the cylindrical surface of the mangle roll 10 is shown to have the grooves 13 extend spirally over the surface thereof. Such grooves 13 are preferably of dove-tailed edge formation and are spaced from one another a uniform predetermined distance.

An efficient method of forming the corkwood facing 14 for such grooves 13 is indicated in Fig. 1, namely, in the form of blocks 15, 16, 17, etc., secured longitudinally to one another by means of adhesive, metal pins or other accepted manner of connection and provided with the bottom extension 18, formed by cutting away the end portions indicated at 19, 20, on the opposite sides of the extension 18. The width of the bottom extension 18 is slightly larger than the width of each dove-tailed groove 13, whereby inserting the bottom extension

18 within a groove 13, the friction of the extension within the groove effects the anchoring of the strip therein, with or without adhesive as desired.

- 5 The width of the upper portion of the strip 14 is selected relatively to the spacing of the grooves 13 whereby upon insertion of the strips 14 in the grooves 13, the strips are brought in substantial contact at their 10 lateral faces to one another. To facilitate the entry of the strip 14 of natural cork-wood within such groove 13, the strip 14 is preferably knife-cut, as at 21, 22, parallel to one another and extending longitudinally 15 of the strip; such knife-cuts 21, 22 are located preferably out of alignment with the lateral edge of the bottom extension 18 and in a region of the upper portion of the cork-wood lying vertically above and within the 20 lateral edges of the bottom extension 18, as is indicated in Figs. 1 and 3.

In Fig. 3, the mangle roll of Fig. 2 is shown on an enlarged scale and it will be observed that the strips 14 of the contiguous 25 grooves 13 engage one another laterally as is indicated at 23, 23. It will be also observed that the knife-cuts 21, 22 enhance the lateral resiliency of corkwood when twisted sufficiently to effect entry within the 30 grooves 13.

For the purpose of providing the aforesaid construction of facing of natural cork-wood for owners or operators of laundering machinery, the facing is marketed in the 35 form of strips having the characteristics shown in Fig. 1 and such strips may be of a length to fill a single groove or of shorter length to enable two or more strips to fill one groove.

- 40 In Fig. 4 I have shown a modified form of strip 25 of natural corkwood formed similarly of blocks 26, 27, etc. secured end to end longitudinally to one another to form a strip of the desired length. In this form of 45 the invention, the respective blocks are provided with the bottom extensions 18 of the construction and arrangement set forth hereinabove in respect to the strip shown in Figs. 1, 2 and 3. However, in the form 50 shown in Fig. 4, the upper portion of the blocks 27 are saw-cut with a relatively wide cut to form a groove 28. The width of the upper face 29 of each strip is less than the spacing between the grooves 13 to thereby 55 provide the clearance 30 between the contiguous lateral faces of the strips 25 of a width substantially equal to the width of the saw-cut groove 28 when opened-out upon insertion of the blocks 25, within the 60 groove 13, as indicated in Fig. 5.

In Fig. 5, I have indicated the groove 13^a appearing at the extreme right-hand side, provided with the anchoring pins 13^b, in which circumstance the edges of the groove 65 13^a is straight, that is, not dove-tailed.

In Fig. 6, I have shown a further modification of the invention, comprising the strip 31 mounted in a carrier 32 of metal or the like having the oppositely disposed upper end flanges 33, 34, providing therebetween a groove for reception therewithin of the bottom extension 18 of the cork strip 31. The carrier 31 is provided with the bottom extension 35 for entry in a groove 13 of the mangle roll 10. In the circumstance of constructing the carrier 32 of steel or like rigid metal, the carrier is preferably provided with the groove or saw-cut 36 on its upper face, which may be centrally thereof to facilitate the necessary twisting of the carrier upon insertion within the spiral groove 13.

As will be perceived from the arrangement shown in Fig. 6, the outer facing or padding of the ironing roll is formed of rows of relatively small blocks 31, of cork arranged side by side and mounted on and secured to a metallic carrier or backing sheet 32. The relatively small blocks of cork, composing the rows constituting the padding for the ironing roll, have the lower part of their sides cut away, as illustrated in Fig. 6, to receive the oppositely disposed, inwardly projecting flanges or ribs 33, 34 of the metal carrier or backing sheet 32, whereby the lower portions of the blocks of cork are narrower than the tops, and also whereby the upper portions of the sides of the blocks of cork project over the ribs 32.

Upon insertion of the cork strips on the mangle roll 10 in the manner as set forth hereinabove, and applying the usual outer coverings of canvas, linen or cotton sheeting or the like, indicated at 12 in Fig. 2, the mangle roll is faced with a material capable of withstanding the pressure required in the ironing operation and at the same time possessing yieldability to permit buttons and like addenda of relatively hard and fragile material to pass between the rolls and the heated bed without injury.

Upon providing the mangle roll with a facing of the above nature, it will be observed that the material of the facing is capable of withstanding the atmosphere of steam in the presence of the necessary elevated temperature required in ironing. If desired, the strip may be dipped in suitable heat-proof and moisture-proof coating material, such as solutions of bakelite, shellac or the like for excluding the moisture from within the pores of the natural cork wood.

Such knife-cuts 21, 22, or saw-cuts 28 afford ventilation of the corkwood to dissipate moisture and heat in the ironing operation, and the same end is secured by spacing the strips of cork-wood from one another, thereby enabling the removal of moisture and heat either by means of the knife-cuts or spacing between the strips or both. If desired, the strips may be formed of blocks

of reduced width and without knife-cuts and the ventilation effected by clearances between the strips from one another.

The manner of securing the corkwood material to the steel roll, as set forth hereinabove, is effected without the use of any material such as the ordinary adhesives for corkwood usually containing albumen, casein or the like, which substances deteriorate in the presence of steam and under the condition of pressure and become putrid, thereby losing their chemical binding effect and creating objectionable odor.

The arrangement of the grooves in a spiral direction about the periphery of the roll enhances the life of the blocks of natural corkwood as compared with grooves arranged substantially parallel to the longitudinal axis of the roll, and it will be observed upon rotation of the roll in either direction, that the strips are successively brought into engagement with the articles to be ironed in a manner to force the strips into increased anchorage engagement with the grooves and in a direction of maximum resistance of the corkwood. In this connection it is pointed out that natural corkwood is cut to have the pores of the corkwood extend from the bottom to the top of the block, as viewed in Figs. 1 and 4, and accordingly the arrangement of the blocks of corkwood as shown in Figs. 1 and 4, presents in the ironing operation the face of each block of corkwood having the maximum coefficient of crushing strength.

Whereas I have described my invention by reference to specific forms thereof it will be understood that many changes and modifications may be made without departing from the spirit of the invention.

I claim—

1. The combination with a mangle roll having spaced spirally arranged grooves on its cylindrical surface, of a plurality of

strips of cork formed of blocks secured end to end to one another and disposed substantially parallel to said grooves, said blocks of cork being provided with slits extending in alignment with one another and substantially parallel to said grooves, the width of said strips corresponding to the spacing of said grooves to thereby provide a substantially complete outer surface of cork.

2. The combination with a mangle roll having spaced spirally arranged grooves on its cylindrical surface, of a plurality of strips of cork formed of blocks secured end to end to one another, the width of said strips corresponding to the spacing of said grooves to provide a substantially complete outer surface of natural cork.

3. The combination of a mangle roll having spaced spirally arranged grooves on its cylindrical surface, a carrier secured in said grooves and strips of cork carried by said carriers respectively, and arranged to provide an outermost surface of cork for the roll.

4. The combination of a mangle roll having spaced, spirally extending grooves on its cylindrical surface, carriers secured in said grooves, and strips of cork carried by said carriers respectively, and arranged to provide an outermost surface of cork for the roll.

5. The combination with a mangle roll of metallic material and having spaced spirally arranged grooves on its cylindrical surface, of a plurality of strips of cork formed of blocks disposed end to end to one another and a plurality of strips of metallic material respectively supporting said strips of cork, the bases of said strips of metallic material extending within said spirally arranged grooves.

In testimony whereof I have signed this specification this 28th day of June 1923.

WILLIAM F. GRUPE.
